Patented Dec. 15, 1970

219,496

LIPSTICK HOLDER

Leon V. Lebedeff, 1620 11th Ave. W.,
Seattle, Wash. 98119

Filed Mar. 24, 1969, Ser. No. 16,407

Term of patent 14 years

Int. Cl. D28—02

U.S. Cl. D86—10

FIG. 1 is a side view of a lipstick holder showing my new design;

FIG. 2 is a front view of the instant design;

FIG. 3 is a back view;

FIG. 4 is a top view;

FIG. 5 is a side view of the base portion of my new design;

FIG. 6 is a side view of the top portion of the design;

FIG. 7 is a plan view of the top surface of the base portion;

FIG. 8 is a front view of the base portion;

FIG. 9 is a top plan view of the top portion of the design; and

FIG. 10 is a bottom view of my design.

I claim:

The ornamental design for a lipstick holder, as shown.
